UNITED STATES PATENT OFFICE

2,049,445

MINING MACHINE

Morris P. Holmes, Claremont, N. H., assignor to
 Sullivan Machinery Company, a corporation of
 Massachusetts

Application October 30, 1933, Serial No. 695,812

37 Claims. (Cl. 262—30)

The invention relates to mining machines, and more particularly to improvements in the swinging mechanism for the cutter bar of a machine for cutting coal.

5 An object of this invention is to provide an improved cutting mechanism. Another object is to provide an improved cutter bar swinging mechanism. Yet another object is to provide an improved cutter bar swinging mechanism having 10 improved driving and controlling means, the improved driving means having incorporated therein improved speed reducing means. Still another object is to provide an improved cutter bar swinging mechanism having embodied there- 15 in improved speed varying means whereby the cutter bar may be swung at variable speeds. Still another object is to provide in a mechanism of the above character improved speed reducing and speed varying means of the so called inter- 20 mittent, variable-speed, continuous-wedge type. Still another object is to provide an improved cutter bar swinging mechanism for a coal mining machine of the flexibly fed, floor cutter type whereby the cutter bar may be swung wholly 25 independently of the machine feeding means. A still further object is to provide an improved independent power swing for the cutter bar of a mining machine of the longwall type. These and other objects and advantages of the invention 30 will, however, hereinafter more fully appear.

In the accompanying drawings there are shown for purposes of illustration one form and a modification thereof which the invention may assume 35 in practice.

In the drawings,—

Fig. 1 is a plan view of a mining machine having embodied therein the illustrative form of the improved cutter bar swinging mechanism.

40 Fig. 2 is a side elevational view of the mining machine shown in Fig. 1.

Fig. 3 is an enlarged fragmentary view of the cutting end of the mining machine shown in Fig. 1, parts of the driving gearing being shown in 45 horizontal section.

Fig. 4 is a longitudinally extending vertical sectional view taken substantially on line 4—4 of Fig. 3.

Fig. 5 is a transverse vertical sectional view 50 taken substantially on line 5—5 of Fig. 3.

Fig. 6 is a transverse vertical sectional view taken on line 6—6 of Fig. 4.

Fig. 7 is an enlarged horizontal sectional view taken on line 7—7 of Fig. 5.

55 Fig. 8 is a detail sectional view showing the

control means for the cutter chain drive clutch.

Fig. 9 is a detail view taken on line 9—9 of Fig. 8.

Fig. 10 is a detail sectional view showing the control means for the variable speed device. 5

Fig. 11 is a detail view taken on line 11—11 of Fig. 10.

Fig. 12 is a vertical sectional view taken on line 12—12 of Fig. 3.

Fig. 13 is a detail vertical sectional view taken 10 on line 13—13 of Fig. 12.

Fig. 14 is a fragmentary plan view of the machine shown in Fig. 1, illustrating a modified form of construction.

Fig. 15 is a fragmentary side elevational view 15 of the machine shown in Fig. 14.

Fig. 16 is a horizontal sectional view taken on line 16—16 of Fig. 15.

In this illustrative embodiment of the invention the improved bar swinging mechanism is 20 shown embodied in a coal mining machine of the flexibly fed, continuous cutter, floor cutter type, although it will be evident that the improved swinging mechanism may be embodied in mining machines of various other types. The mining 25 machine disclosed herein is a longwall machine generally similar to that disclosed in a copending application Serial No. 555,328, filed Aug. 5, 1931, now matured into Patent No. 1,968,769, granted July 31, 1934, and herein generally comprises a machine frame 1 having a plane bottom 30 surface 2 on which the machine is slidably supported for universal movement over the mine floor. As is usual in longwall coal cutting machines, pivotally mounted on one end of the machine frame at 3 for horizontal swinging movement relative thereto is a horizontal plane cutter bar 4 having guided for circulation about its margin a usual cutter bit carrying cutter chain 5, the cutter bar being swingable about its axis 40 into substantially right angle positions at either side of the machine frame and a central position extending lengthwise of the machine frame as is usual in floor type longwall mining machines. The machine frame 1 in this instance 45 comprises a central motor section 6, a cutter carrying section 7 on which the cutter is pivotally mounted and a feed section 8, the motor and feed frame sections being supported on a separate bed frame 9 and the motor section being 50 arranged between the cutter and feed frame sections, these sections when united forming a low compact machine frame. The machine is fed over the mine floor by means of a horizontal feed drum 10 arranged on a vertical axis on the feed 55

frame and cooperating with a feed cable 11. As the method of feeding the mining machine and the particular driving and controlling means for the feed drum are clearly described in the co-pending application mentioned above, further description thereof is herein considered unnecessary.

The means for driving the cutter chain about the margin of the cutter bar in the present instance comprises a spur pinion 15 fixed to the motor power shaft and meshing with a spur gear 16 keyed at 17 to a horizontal longitudinally extending shaft 18 suitably journaled within the cutter frame 7. Formed integral with the gear 16 and driven thereby is a spur gear 19 meshing with a spur gear 20 secured to a sleeve 21 suitably journaled within the cutter frame, as shown in Figs. 3 and 4. Alined with the sleeve 21 is a shaft 22, this shaft being journaled at one end 20 within the sleeve 21 and at its opposite end within the cutter frame. The sleeve 21 is connectible in driving relation with the shaft 22 by a jaw clutch member 23 slidably mounted on the shaft 22 and splined thereto, this clutch member having clutch teeth connectible with clutch teeth formed on the sleeve 21. The clutch member 23 is provided with improved operating means to be later described. Formed on the shaft 22 and driven thereby is a bevel pinion 24 meshing with a large horizontal bevel gear 25 journaled on a vertical shaft 26 secured within the cutter frame. Secured to the hub of the bevel gear 25 and driven thereby is a chain sprocket 27 which engages and drives the cutter chain 5 in a well known manner. The operating means for the clutch member 23 may assume various forms, but in this instance comprises a shipper yoke 28 pivoted at 29 on the cutter frame and having a lever arm 30 pivotally connected at 31 to a link 32. The link 32 is pivotally connected at 33 to a crank 34 fixed to a horizontal operating rod 35 extending longitudinally of the machine frame and suitably journaled in the bed frame 9. Fixed to the rod 35 at 36 is an operating handle 37 conveniently located at the feeding end of the machine remote from the cutting mechanism.

The improved pivotal mounting for the cutter bar 4 comprises a lower annular bearing member 38 formed integral with the bar and journaled on a bearing sleeve 39 surrounding the vertical shaft 26 and supported at the bottom of the cutter frame. The cutter bar has also an integral upstanding portion 40 secured by screws 41 to a bracket member 42 having an upper annular bearing member 43 journaled on a bearing sleeve 44 likewise encircling the shaft 26 and supported at the top of the cutter frame. It will thus be seen that the bearing portions 38 and 39 form a pivotal support for the cutter bar and the cutter bar is guided during its swinging movement by superimposed arcuate flanges 45 formed on the cutter frame and engaging grooves 46 formed on the upstanding frame portion 40 of the cutter support bracket. Formed below the cutter bar is a depending frame support 47 which slidably engages the smooth upper surface of the bottom plate 48 of the cutter frame. It will thus be seen that the cutter bar is mounted for horizontal swinging movement about the vertical axis 3, i. e., the axis of the vertical shaft 26.

Now referring to the improved swinging mechanism for the cutter bar, it will be noted that secured to and driven by the longitudinal cutter drive shaft 18 is a worm 50 meshing with a horizontal worm wheel 51 located above the bevel

gear 25 and having its hub portions journaled on bearing sleeves 52, 52 supported by a sleeve or tubular shaft 53 surrounding the vertical shaft 26. The sleeve is connectible to the worm wheel 51 for driving thereby by means of a multiple disc clutch 54 housed within the worm wheel and having clutch plates keyed to the worm wheel interleaved with clutch plates keyed to the sleeve. The improved means for operating the disc clutch 54 whereby the sleeve 53 may be driven from the worm wheel through a wide range of variable speeds will hereinafter be described. Improved speed reducing means is provided between the sleeve 53 and the cutter bar bearing support 42 and comprises an eccentric portion 55 having rotatably mounted thereon through an anti-friction bearing 56 an annular member 57. Secured as by bolts 58 to a horizontal annular web portion 59 of the cutter frame is an annular guide frame 60 having a plurality of radially 20 located guide chambers or slots 61 in each of which there is slidably guided a plunger 62. These plungers engage in sliding abutting relation the exterior periphery of the ring member 57 and are formed at their outer extremities with tooth-like projections 63 engageable, with a wedging action, with the inclined surfaces of tooth-like portions 64 formed on the upper annular bearing member 43 of the cutter bar mounting. This mechanism forms a speed reducing mechanism between the sleeve 53 and the cutter bar bearing support, and as the eccentric portion 55 is revolved by the worm wheel 51 the plungers 62 are driven radially outwards through the guide frame 60 so that the ends of 30 the plungers engage the inclined sides of the tooth-like projections 64 and thereby transmit rotary motion to the cutter bar bearing member 43 to swing the cutter bar horizontally about the axis of the vertical shaft 26. The operation of 40 the tooth-like plungers is continuous and the elements of this speed reducing mechanism form what might be termed a continuous-wedge, speed reducing mechanism.

The mechanism for controlling the disc clutch 54 to obtain a variable speed drive through this clutch and to provide additional speed reducing means includes on the upper hub portion of the worm wheel 51 a cam-like portion or eccentric 55 with which engages a sliding member or plunger 66 guided in a guideway 67 formed in the transverse web portion 59 of the cutter frame. This plunger has an integral internally threaded portion 68 having adjustably threaded therein at 69 a rod 70. This rod has an enlarged portion 71 with which engages a trunnion device 72 pivotally connected at 73 on a bell crank 74. The other arm of this bell crank is pivotally connected at 75 to a swingable clutch shipper yoke 76. This shipper yoke engages an annular clutch applying member 77 encircling the hub of a member 78 encircling the shaft 26, and this member 77 effects application of the disc clutch through a ball bearing clutch applying member 79. The arms of the yoke act as a lever between the members 65 77 and 78 so that when the yoke 76 is swung upwardly the member 77 is moved upwardly to effect application of the clutch. The cylindrical enlargement 71 of the rod 70 forms a shoulder 80, and a spring 81 is compressed between the outer 70 face 82 of the threaded portion 68 of the plunger and a collar 83 slidably guided upon the rod 70 and normally engaging the shoulder 80 of the rod enlargement. The enlargement 71 of the rod passes through the trunnion device 72, and this 75

trunnion device comprises, as shown in Fig. 13, elements 84, 84 having concave recesses slidably engaging the cylindrical body of the rod enlargement 71, and these elements are pivotally connected at 73 to the bifurcated arm 85 of the bell crank 74. The bell crank 74 is pivotally mounted at 86 on a reciprocable operating rod 87, herein a speed adjusting member, guided within a groove 88 formed in the cutter frame. The means for 10 moving the member 87 inwardly or outwardly to vary the position of the bell crank fulcrum 89 herein, in the preferred form of the invention, comprises a lever arm 89 pivotally connected at 90 to the member 87 and mounted for swinging 15 movement about a vertical axis on a vertical shaft 91. Also mounted on the shaft 91 is a similar lever arm pivotally connected at 92 (see Fig. 10) to a reciprocable operating member 93 guided at 94 within the cutter and bed frames. The 20 member 93 is connected by an adjustable threaded connection 95 to a reciprocable operating member 96 guided within a guideway 97 formed in an upstanding portion 98 of the bed frame 9. Interposed between the upstanding portion 98 of 25 the bed frame and a collar 99 secured to the member 96 is a coil spring 100 for normally urging the member 96 toward its forward position. Pivotally connected by a pin and slot 101 to the outer bifurcated end of the member 96 is an 30 eccentric operating member or cam 102 projecting within and engaging the sides of the guideway 97 in the upstanding frame portion 98 and having an operating lever 104 conveniently located adjacent the lever 31 at the feeding end of 35 the machine. When the lever 104 is in the position shown in Fig. 11 the member 96 is held in its innermost position by the spring 100, but when the eccentric 102 is swung laterally the member 96 is moved rearwardly against the tension of the spring. It will thus be seen that the 40 speed adjusting member 87 may be slid inwardly or outwardly as desired to vary the fulcrum point of the bell crank 74, thereby to vary the time intervals of application of the disc clutch 54. It 45 will thus be seen that when the parts are in the position shown in Fig. 12 and the cam or eccentric 65 is rotated by the worm wheel 51 the plunger 66 is moved axially to the right, swinging the bell 50 crank 74 about its pivot and thereby swinging the shipper yoke 76 upwardly to apply the disc 55 clutch 54. Movement to the right of the rod 70 will result in the transmission of no power to the clutch shipper 76 until the collar 83 engages the trunnion device 72, but further movement to 60 the right of the rod will apply pressure to the clutch and vary the degree of compression of the spring 81. It is therefore evident that as the cam 65 revolves, the shipper 76 is swung back and forth intermittently to apply the disc clutch 54, and as a result, the sleeve 53 is intermittently 65 rotated at a relatively low speed. As above mentioned, the member 87 provides an adjustable fulcrum for the bell crank 74, and upon movement of this member 87 by the handle 104 in an axial direction to the right in Fig. 12 the interval of engagement of the plunger 66 with the cam 65 will be varied, and as a result, the time of application of the disc clutch 54 will be correspondingly varied. Upon movement of the bell crank 70 fulcrum 89 to the right to a position sufficient to bring the plunger 66 out of engagement with the cam, the disc clutch 54 is maintained in released position during rotation of the cam. When the member 87 is moved to the left so far that the 75 collar 83 continuously presses under the pressure of the spring 81 against the trunnion device 72, continuous application of the clutch will take place and the spring 81 will compress during each revolution of the cam an amount substantially equal to the full throw of the cam; but since the 5 load of the spring is above the minimum necessary to effect power transmission through the clutch discs, there will be no release even when the lowest point in the cam is opposite the plunger 66. By moving the member 87 graduated amounts toward the right in Fig. 12, the 10 period of drive during each revolution of the cam may be progressively reduced until it is entirely discontinued. Therefore the drive through the disc clutch 54 may be so adjusted as to obtain 15 a continuous maximum low speed drive and an intermittent low speed drive from said maximum low speed down to zero. As a result, the cutter bar may be swung at a maximum low cutting speed and at intermittent low cutting speeds between said maximum low speed down to zero.

In the modification shown in Figs. 14, 15 and 16, the speed varying member 87 is provided with a reduced threaded end 106 threadedly connected to a nut member 107 having an operating handle 108 and having threaded engagement at 109 with the cutter frame, the member 87 being adjusted directly by the rotatable nut and screw connection, the connections 89, 93, 96, 102 and 104 having been omitted. Also instead of the connections shown in Fig. 8 for operating the cutter chain clutch, the cutter chain clutch in this instance is operated directly by a pivoted lever 110 secured to a transversely extending horizontal shaft 111 which carries the shipper yoke for 30 sliding the jaw clutch member 23. It will thus be seen that in this modified form of construction the cutter chain drive clutch and the speed varying means for the cutter bar swing are operated from the side of the cutter frame adjacent the 40 forward end of the machine instead of through connections extending beneath the motor and feed frames to the opposite or feed end of the machine, and are especially adapted to a machine of the low vein type wherein the motor and feed frames rest directly on the mine floor. Otherwise this form of the invention is the same 45 as that above described.

As a result of this invention, it will be noted 50 that an improved cutter bar swinging mechanism is provided whereby the cutter bar may be swung about its pivot through a wide range of variable cutting speeds. It will further be noted that an improved cutter bar swinging mechanism is provided 55 for a coal mining machine of the flexibly fed, continuous cutter, bottom cutting type whereby the cutter bar may be swung about its pivot wholly independently of the machine feeding means. It will further be noted that an improved 60 cutter bar swinging mechanism is provided which is of an extremely compact and rugged nature and which may be operated and controlled in an improved manner. Other uses and advantages of 65 the improved bar swinging mechanism will be clearly apparent to those skilled in the art.

While there are in this application specifically described one form and a modification thereof which the invention may assume in practice, it will be understood that this form and modification of the same are shown for purposes of illustration and that the invention may be modified and embodied in various other forms without departing from its spirit or the scope of the appended claims.

What I claim as new and desire to secure by Letters Patent is:

1. In a mining machine, a machine frame, a cutter bar pivotally mounted thereon for cutting a plane kerf, and mechanism for swinging said cutter bar about its pivot in its cutting planes including a drive member rotatable about an axis coincident with the bar pivot axis, a member swingable with said cutter bar, and speed reducing means between said drive member and said swingable member including an eccentric, a reciprocable member actuated by said eccentric, and a rotatable member actuated by said reciprocable member and arranged coaxial with the bar pivot.
2. In a mining machine, a machine frame, a cutter bar pivotally mounted thereon and swingable on its pivot to cut a plane kerf, and means for swinging said cutter bar about its pivot including an eccentric rotatable about an axis alined with the bar pivot axis, and variable speed driving connections between said eccentric and cutter bar including a plunger actuated by said eccentric, a lever swingable by said plunger, a drive clutch arranged with its axis in the same plane with the bar pivot, and clutch operating means actuated by said lever.
3. In a mining machine, a machine frame, a cutter bar pivotally mounted thereon and swingable on its pivot to cut a plane kerf, and means for swinging said cutter bar about its pivot including an eccentric rotatable about an axis alined with the bar pivot axis, and variable speed driving connections between said eccentric and cutter bar including a plunger actuated by said eccentric, a lever swingable by said plunger, a drive clutch arranged with its axis in the same plane with the bar pivot, clutch operating means actuated by said lever, and means for varying the position of the lever fulcrum to vary the drive through said clutch.
4. In a mining machine, a machine frame and cutter bar pivotally mounted thereon and swingable on its pivot to cut a plane kerf, and means for swinging said cutter bar about its pivot including an eccentric arranged with its axis alined with the bar pivot axis, and variable speed driving connections between said eccentric and the cutter bar including a plunger actuated by said eccentric, a pivoted lever, a resilient connection between said plunger and lever whereby said lever is swung about its pivot by said plunger, a drive clutch, a shipper member for said clutch, and connections between said lever and shipper member whereby said shipper member is actuated by said lever, and means for varying the position of the lever fulcrum to vary the application of said clutch.
5. In a mining machine, a machine frame, a cutter bar pivotally mounted thereon and swingable on its pivot to cut a plane kerf, a drive member arranged with its axis alined with the bar pivot axis, a speed reducing mechanism connected to the cutter bar, and intermittent, clutch controlled variable speed driving connections between said drive member and said speed reducing mechanism and arranged generally coaxially with the bar pivot.
6. In a mining machine, a machine frame, a cutter bar pivotally mounted thereon and swingable on its pivot to cut a plane kerf, means for swinging said cutter bar about its pivot through a wide range of variable speeds including driving means including a driving element coaxial with the bar pivot, a friction clutch, means actuated by an element of said driving means for intermittently applying and releasing said clutch, and a speed reducing mechanism driven through said clutch and connectible by the latter to said driving element, said latter mechanism operatively connected to said cutter bar.
7. In a mining machine, a machine frame, a cutter bar pivotally mounted thereon and swingable on its pivot to cut a plane kerf, means for swinging said cutter bar about its pivot through a wide range of variable speeds including driving means including a driving element coaxial with the bar pivot, a friction clutch, means actuated by an element of said driving means for intermittently applying and releasing said clutch, and a speed reducing mechanism driven through said clutch and connectible by the latter to said driving element, said latter mechanism operatively connected to said cutter bar, said speed reducing mechanism including a continuous-wedge speed reducing device arranged in the drive between said clutch and said cutter bar.
8. In a mining machine, a machine frame, a cutter bar pivotally mounted thereon to swing relative thereto to cut a plane kerf, and means for swinging said cutter bar about its pivot including a driving element coaxial with the bar pivot and having an eccentric hub, a shaft, a friction clutch for connecting said driving element to said shaft, and means actuated by said eccentric hub for intermittently applying and releasing said clutch.
9. In a mining machine, a machine frame, a cutter bar pivotally mounted thereon to swing relative thereto to cut a plane kerf, and means for swinging said cutter bar about its pivot including a driving element coaxial with the bar pivot and having an eccentric hub, a shaft, a friction clutch for connecting said driving element to said shaft, means actuated by said eccentric hub for intermittently applying and releasing said clutch, and means for varying the time intervals of such application and release.
10. In a mining machine, a machine frame, a cutter bar pivotally mounted thereon to swing relative thereto to cut a plane kerf, and means for swinging said cutter bar about its pivot including a driving element coaxial with the bar pivot and having an eccentric hub, a shaft, a friction clutch for connecting said driving element to said shaft, means actuated by said eccentric hub for intermittently applying and releasing said clutch, and means for varying the time intervals of such application and release including an operating means for said varying means located at the end of the machine remote from the cutter bar pivot.
11. In a mining machine, a machine frame, a cutter bar pivotally mounted thereon to swing relative thereto, and means for swinging the cutter bar about its pivot including an eccentric, a plunger actuated thereby and reciprocable along a line extending radially with respect to the bar pivot axis, a lever, and a yielding connection between said plunger and said lever.
12. In a mining machine, a machine frame, a cutter bar pivotally mounted thereon to swing relative thereto to cut a plane kerf, and means for intermittently swinging the cutter bar about its pivot including a bar swing controlling clutch coaxial with the bar pivot and means for intermittently automatically applying said clutch including an eccentric, a plunger actuated thereby, a lever, a yielding connection between said plunger and said lever including a spring encircling

said plunger and engaging an abutment thereon, and a collar on said plunger, said lever being swung through said spring and collar.

13. In a mining machine, a machine frame, a cutter bar pivotally mounted thereon to swing relative thereto to cut a plane kerf, and means for intermittently swinging the cutter bar about its pivot including a bar swing controlling clutch coaxial with the bar pivot and means for intermittently automatically applying said clutch including an eccentric, a plunger actuated thereby, a lever, and a yielding connection between said plunger and said lever, and a pivoted clutch shipper actuated by said lever.

14. In a mining machine, a machine frame, a cutter bar pivotally mounted thereon to swing relative thereto to cut a plane kerf, and means for intermittently swinging the cutter bar about its pivot including a bar swing controlling clutch coaxial with the bar pivot and means for intermittently automatically applying said clutch including an eccentric, a plunger actuated thereby, a lever, a yielding connection between said plunger and said lever, and means for changing the position of the lever fulcrum to vary the extent of swing of said lever.

15. In a mining machine, a frame, a kerf cutter pivotally mounted on said frame for cutting a plane kerf, and motor operated means for swinging said kerf cutter in its cutting planes about its pivot at a cutting speed including a friction clutch coaxial with the cutter pivot and motor operated mechanism for intermittently applying and releasing said clutch at predetermined timed intervals.

16. In a mining machine, a frame, a kerf cutter pivotally mounted on said frame for cutting a plane kerf, and motor operated means for intermittently swinging said kerf cutter in its cutting planes about its pivot through a wide range of cutting speeds including a friction clutch coaxial with the cutter pivot, motor operated mechanism for intermittently applying and releasing said clutch at predetermined timed intervals, and means operable at will for varying said timed intervals to vary the rate of cutter swing.

17. In a mining machine, a frame, a kerf cutter pivotally mounted on said frame and swingable on its pivot to cut a plane kerf, and motor operated means for swinging said kerf cutter about its pivot including an eccentric member rotatable about an axis coincident with the cutter pivot axis, a cutter swinging element coaxial with said eccentric member and operatively connected to said kerf cutter, a clutch coaxial with said eccentric member, and means actuated by said eccentric member for intermittently applying and releasing said clutch at timed intervals.

18. In a mining machine, a frame, a kerf cutter pivotally mounted on said frame and swingable on its pivot to cut a plane kerf, and motor operated means for swinging said kerf cutter about its pivot including an eccentric member rotatable about an axis coincident with the cutter pivot axis, a cutter swinging element coaxial with said eccentric member and operatively connected to said kerf cutter, a clutch coaxial with said eccentric member, means actuated by said eccentric member for intermittently applying and releasing said clutch at timed intervals, and means for varying the duration of said timed intervals to vary the rate of cutter swing.

19. In a mining machine, a frame, a kerf cutter pivotally mounted on said frame and swingable on its pivot to cut a plane kerf, and motor operated

means for swinging said kerf cutter about its pivot including an eccentric member rotatable about an axis coincident with the cutter pivot axis, a cutter swinging element coaxial with said eccentric member and operatively connected to said kerf cutter, a clutch coaxial with said eccentric member, a plunger actuated by said eccentric member, and means actuated by said plunger for intermittently applying and releasing said clutch at timed intervals.

20. In a mining machine, a frame, a kerf cutter pivotally mounted on said frame and swingable on its pivot to cut a plane kerf, and motor operated means for swinging said kerf cutter about its pivot including an eccentric member rotatable about an axis coincident with the cutter pivot axis, a cutter swinging element coaxial with said eccentric member and operatively connected to said kerf cutter, a clutch coaxial with said eccentric member, a plunger actuated by said eccentric, and yieldable means actuated by said plunger for intermittently applying and releasing said clutch at timed intervals.

21. In a mining machine, a frame, a kerf cutter pivotally mounted on said frame and swingable on its pivot to cut a plane kerf, and motor operated means for swinging said kerf cutter about its pivot including an eccentric member rotatable about an axis coincident with the cutter pivot axis, a cutter swinging element coaxial with said eccentric member and operatively connected to said kerf cutter, a clutch coaxial with said eccentric member, a plunger actuated by said eccentric, and means including a lever actuated by said plunger for intermittently applying and releasing said clutch at timed intervals.

22. In a mining machine, a frame, a kerf cutter pivotally mounted on said frame and swingable on its pivot to cut a plane kerf, and motor operated means for swinging said kerf cutter about its pivot including an eccentric member rotatable about an axis coincident with the cutter pivot axis, a cutter swinging element coaxial with said eccentric member and operatively connected to said kerf cutter, a clutch coaxial with said eccentric member, a plunger actuated by said eccentric, yieldable means actuated by said plunger, and a lever actuated by said plunger through said yieldable means for intermittently applying and releasing said clutch at timed intervals.

23. In a mining machine, a frame, a kerf cutter pivotally mounted on said frame and swingable on its pivot to cut a plane kerf, and motor operated means for swinging said kerf cutter about its pivot including a driving member rotatable about an axis coincident with the cutter pivot axis, an eccentric member coaxial with said driving member, connections between said driving member and said eccentric member for intermittently rotating said eccentric member at predetermined timed intervals, a plunger actuated by said eccentric member and guided on said frame, and a member actuated by said plunger and secured to said kerf cutter.

24. In a mining machine, a frame, a kerf cutter pivotally mounted on said frame and swingable on its pivot to cut a plane kerf, and motor operated means for swinging said kerf cutter about its pivot including a driving member arranged with its axis coincident with the cutter pivot axis, an eccentric member coaxial with said driving member, connections between said driving member and eccentric member for intermittently rotating the latter including a clutch, and means for intermittently applying and releasing

- said clutch at timed intervals, a plunger actuated by said eccentric member and guided on said frame, and a member actuated by said plunger and secured to the kerf cutter.
5. 25. In a mining machine, a frame, a kerf cutter pivotally mounted on said frame to cut a plane kerf, and motor operated means for swinging said kerf cutter about its pivot in its cutting planes through a wide range of cutting speeds including coaxial relatively rotatable driving and driven elements arranged with their axes coincident with the cutter pivot axis, and driving connections between said elements and arranged generally coaxially therewith for intermittently rotating said driven element through a wide range of speeds.
26. In a mining machine, a frame, a kerf cutter pivotally mounted on said frame to cut a plane kerf, and motor operated means for swinging said kerf cutter about its pivot in its cutting planes through a wide range of cutting speeds including coaxial relatively rotatable driving and driven elements arranged with their axes coincident with the cutter pivot axis, driving connections between said elements for intermittently rotating said driven element through a wide range of speeds including a clutch, means driven by an element of the driving means for intermittently applying and releasing said clutch at predetermined timed intervals, and means operable at will for varying the duration of said timed intervals.
27. In a mining machine, a frame, a kerf cutter pivotally mounted on said frame to cut a plane kerf, and motor operated means for swinging said kerf cutter about its pivot in its cutting planes through a wide range of cutting speeds including a driving member arranged with its axis coincident with the cutter pivot axis, a driven member coaxial with said driving member and secured to said kerf cutter, connections between said driving and driven members for intermittently rotating said driven member including a friction clutch, means actuated by an element of said driving means for intermittently applying and releasing said clutch at predetermined timed intervals, and means operable at will for varying the duration of said timed intervals.
28. In a mining machine, a frame, a kerf cutter pivotally mounted on said frame and swingable on its pivot to cut a plane kerf, motor operated means for swinging said kerf cutter about its pivot including an eccentric member rotatable about an axis coincident with the cutter pivot axis, an annular member rotatably mounted on and actuated by said eccentric member, a member having a portion surrounding said annular member and secured to said frame, said last mentioned member having radially located guideways, plungers guided in said guideways and actuated by said eccentric member through said annular member, a toothed member with which said plungers cooperate and secured to the kerf cutter, means for intermittently rotating said eccentric member through a wide range of speeds including a driving element coaxial with said eccentric member, a clutch for connecting said eccentric member in driving relation with said driving element, and means actuated by an element of the driving means for intermittently applying and releasing said clutch at timed intervals.
29. In a mining machine, a frame, a kerf cutter pivotally mounted on said frame and swingable on its pivot to cut a plane kerf, motor operated means for swinging said cutter bar about its pivot including an eccentric rotatable about an axis alined with the bar pivot axis, and variable speed driving connections between said eccentric and cutter bar including a plunger actuated by said eccentric, a lever swingable by said plunger, a drive clutch coaxial with the bar pivot, clutch operating means actuated by said lever, and means for varying the position of the lever fulcrum to vary the drive through said clutch.
30. In a mining machine, a machine frame, a cutter bar pivotally mounted thereon and swingable on its pivot to cut a plane kerf, and motor operated means for swinging said cutter bar about its pivot including a driving member, an eccentric driven thereby, a shaft coaxial with the bar pivot, a clutch for connecting said shaft to said driving member and through which all power is transmitted to effect low speed bar swing, and means actuated by said eccentric for intermittently applying and releasing said clutch at timed intervals.
31. In a mining machine, a machine frame, a cutter bar pivotally mounted thereon and swingable on its pivot to cut a plane kerf, and means for swinging said cutter bar about its pivot including a driving member rotatable about an axis alined with the bar pivot axis, and variable speed driving connections between said driving member and cutter bar for transmitting a swinging force from the former to the latter including a plunger actuated by said driving member, a lever swingable by said plunger, a drive clutch, and clutch operated means actuated by said lever.
32. In a mining machine, a machine frame, a cutter bar pivotally mounted thereon and swingable on its pivot to cut a plane kerf, and means for swinging said cutter bar about its pivot including an eccentric rotatable about an axis alined with the bar pivot axis, and variable speed driving connections between said eccentric and cutter bar including a plunger actuated by said eccentric, a lever swingable by said plunger, a drive clutch coaxial with the bar pivot, clutch operating means actuated by said lever, and means for varying the position of the lever fulcrum to vary the drive through said clutch.
33. In a mining machine, a machine frame and cutter bar pivotally mounted thereon and swingable on its pivot to cut a plane kerf, and means for swinging said cutter bar about its pivot including an eccentric arranged with its axis alined with the bar pivot axis, and variable speed driving connections between said eccentric and the cutter bar including a plunger actuated by said eccentric, a pivoted lever, a resilient connection between said plunger and lever whereby said lever is swung about its pivot by said plunger, a drive clutch coaxial with the bar pivot, a shipper member for said clutch, connections between said lever and shipper member whereby said shipper member is actuated by said lever, and means for vary-

ing the position of the lever fulcrum to vary the application of said clutch.

34. In a mining machine, a machine frame, a cutter bar pivotally mounted thereon to swing relative thereto to cut a plane kerf, means for swinging the cutter bar about its pivot including a drive member coaxial with the bar pivot, an eccentric driven thereby, a plunger actuated by said eccentric, a lever, and a yielding connection between said plunger and said lever through which the latter is actuated by said plunger.

35. In a mining machine, a machine frame, a cutter bar pivotally mounted thereon to swing relative thereto to cut a plane kerf, means for swinging the cutter bar about its pivot including a drive member coaxial with the bar pivot, an eccentric driven thereby, a plunger actuated by said eccentric, a lever, a yielding connection between said plunger and said lever through which the latter is actuated by said plunger including a spring encircling said plunger and engaging an abutment thereon, and a collar on said plunger, said lever being swung through said spring and collar.

36. In a mining machine, a machine frame, a cutter bar pivotally mounted thereon to swing relative thereto to cut a plane kerf, means for swinging the cutter bar about its pivot including a drive member coaxial with the bar pivot, an eccentric driven thereby, a plunger actuated by said eccentric, a lever, a yielding connection between said plunger and said lever through which the latter is actuated by said plunger, and a pivoted clutch shipper actuated by said lever.

37. In a mining machine, a machine frame, a cutter bar pivotally mounted thereon to swing relative thereto to cut a plane kerf, means for swinging the cutter bar about its pivot including a drive member coaxial with the bar pivot, an eccentric driven thereby, a plunger actuated by said eccentric, a lever, a yielding connection between said plunger and said lever through which the latter is actuated by said plunger, and means for changing the position of the lever fulcrum to vary the extent of swing of said lever.

MORRIS P. HOLMES.
